BY Louis Barnett.

ATTORNEY

UNITED STATES PATENT OFFICE

SAMUEL RICHMAN, OF BROOKLYN, NEW YORK

TIE

Application filed January 29, 1930. Serial No. 424,169.

This invention relates to ties, and more particularly is directed to novel neck-size adjusting constructions adapted to be incorporated in four-in-hand and string or tying bow ties.

One object of the invention is to provide improved ties of the character described adapted to be conveniently fitted and worn on any size or style collar.

10 Another object of the invention is to provide in ties of the character described improved length adjustment means for easily and quickly fitting various collar sizes to assume proper tying styles or for shifting 15 the knotting tie portions.

A further object of the invention is to provide in ties of the character described, an improved collar size adjustment means including collar attachment portions.

20 Still another object of the invention is to provide improved ties of the character described, each including few and simple neck-size adjusting parts, which shall be easy to assemble, which shall form a neat and attractive apparel with the size adjusting parts inconspicuously incorporated therein, and which shall be inexpensive to manufacture and practical and efficient to a high degree in use.

30 Other objects of this invention will in part be obvious and in part hereinafter pointed out.

The invention accordingly consists in the features of construction, combinations of 35 elements and arrangement of parts which will be exemplified in the constructions hereinafter described and of which the scope of application will be indicated in the following claims.

40 In the accompanying drawing in which is shown various possible illustrative embodiments of this invention—

Fig. 1 is a perspective view of a string or tying style bow tie constructed to embody 45 the invention showing the inner side of the size adjustable neck band portion.

Fig. 2 is a fragmentary perspective view showing the outer side of the improved tie size adjustable neck band.

50 Fig. 3 is a fragmentary view of the tie

neck band, shown in Fig. 1, partly cut away along lines 3—3 to expose the improved length or size adjusting means.

Fig. 4 is a fragmentary, enlarged perspective view of the link and loop connections, as shown in Fig. 1.

Figs. 5 and 6 are fragmentary, perspective views showing two other improved forms of link and loop connections embodying the invention, and

Figs. 7 and 8 are cross sectional views showing the invention applied to secure detachable collars, the tie band sections shown corresponding to cuts taken on lines 7—7 and 8—8, respectively, in Figs. 4 and 5, respectively.

Referring in detail to the drawing, 20 denotes a string or tying type of bow tie constructed to embody the invention.

Said tie 20 is seen to comprise two parts 70 21, which preferably, for this type of tie, are identical in size and shape. Each part 21 may be made of any suitable material such as, natural or artificial silk, cotton, wool, linen or other textile cloth, and is usually formed of 75 an outer or front layer 22, an inner or back layer 23 and a lining 24, all secured together by stitching (not shown) in the well understood manner.

The free ends 25 of the tie 20, each forming 80 one end of a part 21, is fashioned for tying a desired shape of bow. The other ends 26 of the part 21, forming the neck band portion of the tie, are looped at 27 through the opening 28a of a link 28 for interconnecting 85 said tie parts 21. The portions 26a of the ends 26, extending beyond the loops 27 are carried back and are secured by suitable detachable fasteners 29 to the adjacent portions of the tie neck band portions as is shown 90 in Figs. 1 and 3.

The link 28 may be made of a metal stamping or bent wire and has the length of its opening 28a formed to neatly accommodate the width of the ends 26. The link 28 has 95 arms 30, which are embraced by the loops 27, said arms being parallelly spaced apart substantially, a distance equivalent to the thickness of the materials of said loops so that the latter are in abutment and the outer side of 100

the tie neck band portion appears to be continuous and neat appearing since the link is practically inconspicuous. See Fig. 2.

Where the tie 20 is to be worn on a shirt having a detachable collar, the link 28 may be provided with an anchoring extension or tongue 31 at one end thereof. In the form shown in Fig. 4, said tongue 31 comprises the centre portion of the link stamping which is displaced in providing the opening 28a. Said tongue 31 may be positioned to lie in a plane substantially parallel to that of the link arms. Referring now to Fig. 7, the tongue 31 is here shown to replace the usual back collar button since it may be inserted through the button holes 32a and 33a of the shirt band 32 and collar 33, respectively. When thus used as is now readily understood, said extension tongue serves to retain both the collar 33 and tie 20 attached to the shirt collar band 32.

The fastener 29 may be of any conventional type, such as a hook and eyelets, or, preferably snap fasteners. The female portions 29a of the fastener 29 is secured to the inner layer 23 on each end 26 of a tie parts in such spaced relation as to correspond to the standard neck sizes, 14, 15, 16, 17, etc., and a co-operating male portion 29b is provided on said layer 23 adjacent the extreme end of the tie part 21, as shown in Fig. 3.

Suitable size markers or indicating means 34 may be provided on each of said tie ends 26. As here shown said size markers 34 comprise tabs 35 extending from the female portions 29a on which the size numeral is imprinted.

The practical application of the invention will now be apparent. The tie 20 is constructed and assembled as described above and shown in Figs. 1 to 3, inclusive. To vary the neck-size of the tie 20, that is, to change the tie length, the snap fastener male portion 29b is simply attached to the female portion 29a marked with the neck size numeral desired and the loop 27 moved through the link 28 until all the slack is taken out of the tie end 26. In case the tie 20 is used for a small neck size only, a second snap fastener male portion 29b may be provided to engage with one of the intermediate female portions as shown in Fig. 3.

The use of the tongue 31 extending from the link 28 has already been described above in connection with Fig. 7.

In Figs. 5 and 8, a modified form of the invention is shown, here the link 128 is made with a tongue 131 extending from one end thereof. Said tongue is bifurcated and is adapted to engage over the head 40a of a back collar button 40 which retains the collar 33 to the shirt collar band 32. This form of link 128 serves to retain the tie from displacement, when once applied to engage the tongue 131 with the collar button head 40a.

In Fig. 6, the link 228 shown is formed of wire instead of being stamped from sheet metal. This link may be used for anchoring the tie either like the link 28 or 128 shown in Figs. 7 and 8, and described above.

This invention when applied to four-in-hand ties (not shown) permits varying the length of the tie so that the exposed knotted portion of the tie can be shifted when it is soiled or becomes otherwise unsightly.

It will thus be seen that there is provided devices in which the several objects of this invention are achieved and which are well adapted to meet the conditions of practical use.

As various possible embodiments might be made of the above invention, and as various changes might be made in the embodiment above set forth, it is to be understood that all matters herein set forth or shown in the accompanying drawing are to be interpreted as illustrative and not in a limiting sense.

Having thus described my invention, I claim as new and desire to secure by Letters Patent:

1. A tie comprising two separable parts, each of said parts having at one end thereof a portion adapted to form a knot with the corresponding portion of the other part, the other end of each of said tie parts having a plurality of companion separable fasteners all on one surface thereof whereby said end may be formed into a detachably secured loop of variable length in each tie part, and a link member having spaced side portions, one of which engages the loop of one tie part and the other of which engages the loop of the other tie part.

2. A tie comprising two separable parts, each of said parts having at one end thereof a portion adapted to form a knot with a corresponding portion of the other part, the other end of each of said tie parts having a plurality of companion separable fasteners all on one surface thereof whereby said end may be formed into a detachably secured loop of variable length in each tie part, a link member having spaced side portions, one of which engages the loop of one tie part and the other of which engages the loop of the other tie part, and an anchoring extension projecting from said link member for detachably securing the tie in position.

In testimony whereof I affix my signature.

SAMUEL RICHMAN.
